(57) **CLAIM**

The ornamental design for a housing for communications equipment, as shown and described.

DESCRIPTION

FIG. 1 is a front perspective view of a housing for communications equipment showing our new, original, and ornamental design;

FIG. 2 is a front view of the housing for communications equipment of FIG. 1;

FIG. 3 is a rear view of the housing for communications equipment of FIG. 1;

FIG. 4 is a left side view of the housing for communications equipment of FIG. 1;

FIG. 5 is a right side view of the housing for communications equipment of FIG. 1; and,

FIG. 6 is a top view of the housing for communications equipment of FIG. 1.

The broken lines depict portions of the article that form no part of the claimed design.

1 Claim, 6 Drawing Sheets
